UNITED STATES PATENT OFFICE.

ABRAHAM GERSTENZANG, OF NEW YORK, N. Y.

TOOTH-BRUSH.

1,192,298.

Specification of Letters Patent. Patented July 25, 1916.

Original application filed October 6, 1913, Serial No. 793,545. Divided and this application filed March 29, 1915. Serial No. 17,585.

To all whom it may concern:

Be it known that I, ABRAHAM GERSTENZANG, a citizen of the United States, and a resident of the borough of the Bronx, county 5 of Bronx, city and State of New York, have invented a certain new and useful Tooth-Brush, of which the following is a specification.

This is a division of my application for 10 patent filed October 6, 1913, Serial No. 793,545.

The object I have in view is the production of an entirely portable and satisfactory tooth brush.

15 Further objects are to produce a brush, which may be firmly held in the hand while in use, and in which the handle may be cleansed.

A further object is to increase the facility 20 of removal from the carrying case.

These and further objects will more fully appear from the following specification and accompanying drawings, considered together or separately.

25 In the drawings, Figure 1 is a plan view of a brush embodying my invention in collapsed form and located within a carrying case; Fig. 2 is a side view of the same, portions of the brush and the case being shown 30 in section; Fig. 3 is an elevation of a brush in extended position; and Fig. 4 is a sectional view of the same.

In all views like parts are designated by the same reference characters.

35 The brush illustrated is formed of a body 1 made of any material. The body is preferably made with a short length of handle section and a back portion, to which the bristles are attached, offset relatively to the 40 handle section so that the latter will be in line with the longitudinal center of the brush, as a whole. By this construction the compactness of the device will be increased. In connection with the body is a handle 2.

45 This handle is collapsible, it being made telescopic for this purpose. It comprises a plurality of frusto-conical sections 3. These sections may be nested one with another as shown in Fig. 2 in which event the tooth 50 brush will be sufficiently short to go within a casing α of small size. The handle may be extended as shown in Figs. 3 and 4, in which event the handle will be long enough and rigid enough for use. To assist in the security of connection of the sections, they

may be screw-threaded as shown in Fig. 4. In order to make the brush more effective with a handle of limited length, the free end section is provided with a curvature 4 so that the thumb of one hand may be applied 60 to it and the brush manipulated with greater steadiness than without it. Also to permit the cleansing of the handle, the end section is left open as shown. To assist in the withdrawal of the brush from the casing α it is 65 provided with a notch 5 to permit the introduction of the finger nail of the user. The offset of the body 1 is of such extent that none of the frusto-conical members will be capable of passing over the body, thereby 70 preventing removal of the said parts in the direction of the body of the brush. The parts will be prevented from being separated by movement in the other direction by reason of the fact that the inner end of each 75 section is of less diameter than the outer end of the adjoining section. By this construction the frusto-conical members are always open thus providing means for keeping the brush in a sanitary condition. 80

In accordance with the provisions of the patent statutes, I have described the principle of my invention, together with the apparatus which I now consider to represent the best embodiment thereof; but I desire to 85 have it understood that the apparatus shown is merely illustrative and that the invention may be carried out in other ways.

Having now described my invention, what I claim as new and desire to secure by Letters Patent, is:

1. A tooth brush having a back, a range 95 of bristles, a handle section offset relatively to the back, and a movable member engaging the handle section, said member and section being in line with the longitudinal center of the brush, the lateral dimensions of the handle section and member being less than a lateral dimension of the back and range of bristles. 100

2. A tooth brush having a back, a range of bristles, a handle section offset relatively to the back, and a plurality of movable members engaging the handle section, and one within another, said members and section 105 being in line with the longitudinal center of the brush, the lateral dimensions of the section and outside member being less than a lateral dimension of the range of bristles and the back. 110

3. A tooth brush having a back, a range of bristles, a handle section offset relatively to the back, a plurality of movable members engaging the handle section, and one with 5 in another, said members and section being in line with the longitudinal center of the brush, and each of a diameter less than the lateral dimension of the back and bristles, and means for securing the members together 10 and to the section against movement in any direction.

4. A tooth brush having a back, a range of bristles extending longitudinally of and projecting from one side thereof, a handle section integral with the back and offset relatively thereto, said section extending in 15 the same longitudinal direction as the back and in line with the longitudinal center of the brush, screw threads on the extremity 20 of the section, a tubular member, a female thread on the member and engaged by the thread on the section, a male thread on the opposite end of the member, a second tubular member having a female thread engaging the male thread on the first mentioned 25 member, the diameter of the second tubular member being less than the greatest lateral dimension of the range of bristles and the back.

5. A tooth brush having a back, a range

of bristles, a handle section offset relatively to the back, a plurality of hollow, open ended movable members engaging the handle section and one within the other, said members and section being in line with the longitudinal center of the brush, the diameters of the members being less than the lateral dimension of the back and bristles, and means for securing the members together and to the section against movement in any 40 direction.

6. A tooth brush having a back, a range of bristles, a handle section offset relatively to the back, a plurality of hollow, open ended, movable members engaging the 45 handle section and one within the other, the outermost section having an arc shaped notch in its extremity for engagement of the fingers, said members and section being in line with the longitudinal center of the 50 brush, and means for securing the members together and to the section against movement in any direction.

This specification signed and witnessed this 27th day of March, 1915.

ABRAHAM GERSTENZANG.
